UNITED STATES PATENT OFFICE.

AUGUST J. KREUZKAMP, OF CHICAGO, ILLINOIS, ASSIGNOR TO THE ENGLANDER SPRING BED COMPANY, OF BROOKLYN, NEW YORK, A CORPORATION OF NEW YORK.

BED.

1,413,594.

Specification of Letters Patent. Patented Apr. 25, 1922.

Application filed June 4, 1921. Serial No. 475,005.

To all whom it may concern:

Be it known that I, AUGUST J. KREUZKAMP, a citizen of the United States, residing at Chicago, in the county of Cook and State 5 of Illinois, have invented certain new and useful Improvements in Beds, of which the following is a specification.

This invention relates to beds, an object thereof being to provide a bed having a receptacle or tray section supported by the framework thereof for sliding movement and adapted for the purpose of conveniently storing bed clothes or other articles. An object of the present improvement is to provide a bed wherein the spacing bars connected to the head and foot thereof are utilized as supporting means for the sliding storage receptacle or tray whereby the same may be supported or carried by the bed frame relatively high above the floor and between the spacing bars and mattress fabric. As a result of this improved construction the receptacle, located as near the top of the bed as practicable, is readily accessible to the user, 20 conveniently located, and supported for shiftable movement by the framework without any substantial or expensive modification thereof, thereby resulting in a novel, efficient, and cheap structure.

30 A further object of my invention is to provide a knockdown, four part bed structure comprising a head, a foot, a mattress section detachably carried thereby, and a removable sliding storage receptacle having its supporting framework adapted to assist in supporting the mattress section upon the floor when detached from the head and foot, the construction being such that irrespective of the combined weight of the mattress section and the receptacle, the same may be detached from the head and foot without necessitating the removal of the receptacle.

40 Other objects of my invention will appear in the following description thereof, reference being had to the accompanying drawing forming a part of the specification, wherein like reference characters indicate corresponding parts in the several views and wherein Fig. 1 is a perspective view of a bed structure embodying my invention, the sliding tray being shown in partly open position; Fig. 2 is an end elevation partly in section illustrating the same; Fig. 3 is a fragmentary perspective view illustrating 45 certain parts of my improved structure and

the manner of connecting the mattress with the foot; and Fig. 4 is a detail view illustrating the manner of connecting the mattress section with the head.

In carrying out my invention, the preferred form thereof being illustrated in the accompanying drawing, I have provided in general a knockdown bed comprising a head and foot, a spring mattress section detachably connected thereto, and a removable sliding storage receptacle or tray section preferably of less length than the length of the bed, adapted for the purpose of storing bed clothes or other articles, and having its supporting framework formed by side bars or spacing bars connected to the ends of the mattress section whereby the same is located as far as possible from the floor so as to be conveniently accessible to the user, and at the same time the mattress section may be detached from the head and foot without requiring the removal of the receptacle and its contents. It will be seen that this tray or receptacle is located between the spacing bars of the bed section and the metallic or spring fabric thereof.

The main bed section in the present instance comprises a head 9 and a foot 10, each of which in the present instance consists of a main top or cross member terminating at the ends thereof in legs 11 connected by a cross member or bar 12. The spring mattress frame comprises a pair of end members 13 to which a spring fabric 24 is connected in the usual manner, and in the present instance each of these end members is shown as formed of angle iron and is provided with depending portions 14. These depending portions 14 at their lower ends are connected by spacing bars 15, preferably constructed of angle iron, which maintain the ends properly spaced apart when the spring fabric is stretched therebetween.

50 Each of the legs 11 of the head and foot is provided on its inner side at a predetermined distance below the top of the spring with inwardly extending headed pins 32. Each of the depending portions 14 is provided with a notch or slot 33 for the reception of the headed pins 32. The head 9 at each side is provided at a point adjacent to the top of the spring with a vertically swinging hook 30, pivoted to the inner side of the leg. The foot 10 has the horizontal 55

upper cross member thereof substantially in alignment with the corresponding member 13 of the mattress section, and this cross member, preferably centrally thereof, is provided 5 with a laterally swinging hook so pivoted as to have also a limited or restricted downward swinging movement just sufficient to permit the hooked portion to hook over the end bar 13 and, when detaching the parts, 10 to be lifted to clear the bar so as to be swung laterally out of the way.

It will thus be observed that the detachable mattress section 24 is connected with the head and foot at the bottom thereof by 15 pin and slot connections, and at the top the head 9 is connected to the mattress section by vertically swinging hooks, and the foot 10 is connected to the mattress section by a single horizontally swinging hook 31 having 20 a restricted vertically swinging movement. Said hooks are adapted to hook over the end bars of the mattress section and act to wedge the mattress section into tight engagement with the head and foot, thus preventing 25 any shaking or wobbling joints. In detaching the parts the hooks are released and shifted away from the members 13, before the mattress is handled, and then the head or foot is swung away from the mattress 30 section and the same readily lifted from the pins 32 and lowered to the floor. Thus it is not necessary to maintain the members 14 and 11 in parallel relation in order to disconnect the pin and notch connection, and 35 furthermore this swinging movement of the head and foot tends to loosen the connections, and so there is no possibility of a binding or sticking action when detaching the mattress section.

40 A suitable distance from the ends of the mattress section, cross bars 16, preferably of angle iron, are connected to the side bars 15 of the framework. These cross bars are secured thereto in such manner that the horizontal flanges 17 thereof in conjunction with the horizontal flanges of the side bars 15, will form supporting tracks or ways for a storage receptacle or tray section 18. This receptacle may be of any desired shape or 45 construction and it will be seen in the present instance that the same is of less length than the length of the bed, although it is to be understood that the same may be of any desired length according to the location of 50 the cross bars 16 relative to the mattress section.

55 In order to support the receptacle or tray adjacent to the center thereof while in its normal position between the spacing bars 15 and the spring mattress 24 a suitable angle bar or other member 19 may be secured to the bars 15 intermediate the cross bars 16. It will be seen that the construction is such that the receptacle or tray 18 is free to slide 60 on the ways or tracks 17 beyond either side

of the bed. Thus the user may shift the same to an open position from his position at either side of the bed, and as a result of this facile and inexpensive construction the receptacle is rendered accessible in a most 70 convenient manner.

Thus due to the great ease with which the mattress section may be detached from the head and foot, without necessitating the maintaining of the upright members 14 and 75 11 in parallel relation, and without any binding or sticking of the connecting parts, this may be accomplished easily irrespective of the weight of the parts. Hence the construction permits the mattress section to be 80 detached and lowered to rest upon the floor without necessitating the removal of the bulky receptacle 18 and its contents. When thus detached the mattress will be supported on the floor by the supporting members 85 15 of the receptacle and the depending portions 14, and in such position the receptacle may be readily removed or withdrawn without having to lift the same and its contents. A great saving in time, effort, and labor in 90 the manipulation of the parts thus results from this improved detachable bed structure.

Although I have described my invention in its preferred form it is to be understood 95 that I do not limit myself to the construction herein shown and described except in so far as defined in the claims and embraced within the scope thereof.

I claim as my invention:

1. In a bed structure the combination of 100 a mattress section comprising end members connected together by a spring fabric, spacing bars connected to said end members and constructed to form with the fabric a housing space for a storage receptacle, horizontal ways carried by said spacing bars, and a receptacle supported upon said ways for sliding movement between the spacing bars and the fabric.

2. In a bed structure the combination of 105 a mattress section comprising end members connected together by a spring fabric, said end members terminating each in depending portions, spacing bars connected to said depending portions adjacent to the lower ends thereof, and constructed to form with the fabric a housing space for a receptacle, horizontal ways carried by said spacing bars and a receptacle supported upon said ways for 110 sliding movement between the spacing bars and the mattress fabric.

3. In a bed structure the combination of 115 a head and a foot, a mattress frame adapted to be connected thereto and comprising end members terminating in depending portions, and a fabric stretched between the members, spacing bars connected to the depending portions adjacent to the lower ends thereof and constructed to form a housing space be- 120 125 130

- tween the same and the fabric for a receptacle, and a sliding receptacle carried upon said spacing bars for movement between the same and the mattress fabric.
- 5 4. In a bed structure the combination of a spring mattress frame comprising end bars terminating in depending members and a spring fabric stretched between said bars, side bars connecting the depending members together at each side and constructed to form between the same and the fabric a housing space for a receptacle, horizontal ways supported upon the side bars at right angles to and above the same, and a sliding 10 receptacle adapted to be supported upon said ways between said bars and the spring mattress, said receptacle being of less length than the spring mattress section, and having a shiftable movement in opposite directions 15 beyond said spacing bars.
5. A knockdown bed structure comprising a head and a foot, a mattress section detachably connected thereto, the same comprising transverse end bars terminating in depending members and a fabric stretched there- 20 between, spacing bars connected to the depending members and constructed to form a housing space between the same and the the

fabric for a receptacle, and a receptacle supported by said spacing bars for slidable 30 movement between the same and the mattress, the construction being such that upon detaching the mattress section said depending members and spacing bars will support the same and said receptacle upon the floor. 35

6. A knockdown bed structure comprising a head and a foot, a mattress section detachably connected thereto, the same comprising transverse end bars terminating in depending members and a fabric stretched 40 therebetween, spacing bars connected to the depending members adjacent to the ends thereof and constructed to form a housing space between the same and the fabric for a receptacle, cross bars secured to the spacing 45 bars and adapted to form horizontal ways, and a receptacle supported by said cross bars for slidable movement between same and the mattress, the construction being such that upon detaching the mattress section said depending members and spacing bars will support the same and said receptacle upon the floor. 50

Signed at Chicago, Illinois this 31st day of May, 1921.

AUGUST J. KREUZKAMP.
